(Cl. D25—1)

To all whom it may concern:

Be it known that we, Teofil L. Bonkowski and Harry Solloway, both citizens of the United States and both residing in Los Angeles, in the county of Los Angeles and State of California, have invented a new, original, and ornamental Design for a Musical Toy, of which the following is a specification, reference being had to the accompanying drawings, forming a part thereof.

We claim:

The ornamental design for a musical toy, substantially as shown.

TEOFIL L. BONKOWSKI.
HARRY SOLLOWAY.
